UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE BORING AND CUTTING MACHINE.

1,129,947.

Specification of Letters Patent.

Patented Mar. 2, 1915.

Application filed March 15, 1909. Serial No. 483,578.

To all whom it may concern:

Be it known that I, HENRY F. BECHMAN, of Battle Creek, in the county of Calhoun and State of Michigan, have invented certain new and useful Improvements in Stereotype-Plate Boring and Cutting Machines; and I hereby declare that the following is a full, clear, and exact description thereof, reference being had to the accompanying drawings, which form part of this specification.

This invention is a novel machine for boring and trimming tubular stereotype plates and is particularly designed for finishing the tubular plates produced by the stereotype casting apparatus shown in my application #484,616 filed March 20, 1909, such as are used in my single-plate rotary presses shown in my Patent No. 867230 dated October 1, 1907, and application No. 483,600 filed March 15, 1909. Such plates are substantially tubular in form and are preferably but one page in width and one page in length and are adapted to substantially surround the entire circumference of the plate cylinder in the press, which cylinders are of very small diameter. It is necessary that such single page tubular plates should fit accurately upon such plate cylinders, and should be trimmed to exact length; and the objects of the present invention are to bore such plate, or dress it internally, to the exact diameter requisite to cause it to fit snugly on the plate cylinder; to cut off the head of metal formed on one end of the plate in the casting operation; and to trim such end of the plate accurately so that when the plate is put on the cylinder it can be readily secured in correct position, and will print uniformly on the web.

The present invention therefor embodies novel means for holding and rotating the plate while being bored and trimmed; novel means for operating the boring tools; and novel means for cutting the surplus metal head off of the plate, and for trimming and beveling its end.

In the accompanying drawings I have illustrated a machine embodying these features, and the description of such machine will impart a clear understanding of the invention, and the claims summarize the invention and features thereof for which protection is desired.

In said drawings—Figure 1 is a front

elevation of the machine showing a plate in position for trimming. Fig. 2 is a plan view of Fig. 1. Fig. 3 is a transverse section on line 3—3, Fig. 2. Fig. 4 is a longitudinal section on line 4—4, Fig. 2. Fig. 5 is a transverse section on line 5—5, Fig. 2. Fig. 6 is a detail view of one of the clutch members. Fig. 7 is a transverse section on line 7—7, Fig. 2. Fig. 8 is a plan view of the longitudinal rib detached. Figs. 9 and 10 are detail views of the cutting and trimming tool.

Mounted on a supporting frame or table 1 of any suitable form are a pair of axially aligned bearings 2, in which is rotatably journaled a hollow cylinder, or tubular plate holder 3, whose internal diameter is exactly equal to the external diameter of the finished tubular stereotype plate, when fitted on the cylinder, and whose length is slightly less than the length of such plate. The bearings 2 may conveniently be cast integral with a base plate 2^a so that they can be readily fastened to the frame 1.

On one end of the cylinder or plate-holder 3 is a gear 3^a which meshes with a pinion 4^a on a shaft 4 journaled in a bracket 1^a attached to the frame 1, the shaft 4 lying at one side of the axis of the sleeve and parallel therewith; and pinion 4^a on shaft 4 in turn meshes with a pinion 5^a on a shaft 5 journaled in a bracket 1^b attached to the frame 1; shaft 5 lying parallel with the plate-holder 3, at one side of the bearings 2. Shaft 5 is provided with a pulley 5^b which can be belted to any suitable driver. In this manner the plate-holder 3 can be rotated in the bearings 2.

The plate-holder 3 is provided with a longitudinal rib 3^b on its inner face, said rib forming an abutment for one edge of a tubular plate P when the latter is inserted in the plate-holder, as shown. This plate P as will be seen by reference to Fig. 3 is tubular, but has a narrow longitudinal slot p at one side which equals the distance between consecutive impressions to be made on the web. When a plate P is placed in the cylinder its slot p registers with the rib 3^b.

Pivoted on the plate-holder 3 intermediate the bearings 2, are two plate clamps, which as shown are preferably shaped like bell-crank levers, whose short arms 3^c project through slots in the sleeve and lie in notches in the bar 3^b; while their outer arms

3^d extend substantially at right-angles to arms 3^a and lie close to the outer surface of the plate-holder. These clamps have trunnions 3^e which are confined in slots in the plate-holder by means of straps 3^f. Through the outer ends of arms 3^d are tapped thumb-screws 3^g which bear against the surface of the plate-holder; and these arms 3^d are engaged and normally held down by springs 3^h attached to the exterior of the plate-holder. When the screws 3^g are loosened springs 3^h rock the clamps on their pivots 3^e and hold arms 3^d retracted into the notches in the bar 3^b; but if the screws 3^g are turned inward the clamps can be rocked so as to project arms 3^c beyond the edge of the bar 3^b, (see Fig. 3.) Before a plate P is slipped into the plate-holder 3 the screws 3^g are loosened, and arms 3^c are retracted as described; then the plate P can be slipped into the plate-holder, the bar 3^b occupying the slot p in the plate;—then the screws 3^g are turned inward causing arms 3^c to engage the plate at one edge of the slot p, and tend to turn the plate in the plate-holder, but this rotary movement of the plate is prevented by the engagement of the other edge of the slot p with the opposite side of the bar 3^b, consequently the plate P will be expanded within and against the inner surface of the plate-holder 3, and will be securely clamped in this expanded position; and while the plate is so held the plate-holder is rotated, thereby rotating the plate, and during such rotation the boring and trimming operations are effected as herein-after explained.

The plate-holder 3 is preferably lined internally with a copper sheet, indicated at 3ⁱ, the outer edge of such sheet being spun up against the end of the plate-holder; such copper lining reduces the friction and prevents scratching the surface of the plate P while being slid in or out of or expanded within, the plate-holder.

The plate trimming devices.—On the forward end of frame 1 is mounted a slide 6 which is adapted to be moved transversely of frame 1, between suitable guides 1^c attached to the frame. Said slide has an up-standing lug 6^a which is perforated for the passage of a tool clamp 6^b, which holds a cutter and trimming tool 6^c. This tool, see Figs. 2, 9 and 19, has a straight cutting chisel point 6^d and a beveled cutting and trimming edge 6^e, in rear of the point. The plate 6 is also provided on its under side with a perforated internally threaded lug 6^f which depends through a slot 1^d in the top of the frame 1 and is engaged by a threaded shaft 6^g, which is supported in suitable bearings in the frame 1 and is provided on its outer end with a handle 6^h. By turning this shaft the slide 6 can be moved transversely of the frame, and the

cutter moved to and from the plate-holder. The tool 6^c is so located relative to the plate-holder that when a plate is properly positioned in the plate-holder and the cutter is advanced, it will first cut the head off of the plate by means of point 6^d the plate being rapidly rotated by and with the plate-holder; and then by further advancing the tool 6^c the beveled cutting edge 6^e of the cutter will engage the edge of the plate and trim it down and bevel such edge as is desired to prepare it for engagement with the cylinder-plate clamps. The tool 6^c can then be retracted out of the way by properly manipulating the shaft 6^g.

The boring devices.—Arranged axially of the plate-holder 3 and projecting therethrough is a bar 7, which also extends through the bracket 1^a and is thereby supported upon the frame 1, the bar 7 being located at one side of the bearing of the shaft 4. In the under side of bar 7 is a longitudinal groove in which is mounted a slideable rack 8^c which also passes through a slot in the bracket 1^a. The forward end of rack 8^c is fastened to a tool-carrier 8 slidably mounted on the bar 7, and carrying adjustable trimming tools or cutters 8^a which are secured thereto by bolts 8^b. The carrier 8 can be moved longitudinally on bar 7 by shifting the rack 8^c. To the rear of rack 8^c is connected a strap or rope 8^d which runs over a pulley 7^a hung on the rear end of bar 7 and has a weight 8^e attached to its free end, said weight being sufficiently heavy to normally draw the tool carrier 8 back against the bracket 1^a, thereby withdrawing trimmers 8^a from operative position within the plate-holder 3.

The tool carrier 8 may be moved inward, when desired by the operator, by means of a pinion 8^f meshing with rack bar 8^c and mounted on a transverse shaft 8^g having bearings in brackets 1^e attached to frame 1; said shaft extending to the shaft 4 and having a worm-gear 8ⁱ meshing with a worm 4ⁱ on shaft 4. The pinion 8^f is loose on the shaft 8^g, but may be locked thereto, when desired, by means of a suitable clutch. As shown in Figs. 5 and 6 gear 8^f has a clutch-face 9^c on one face adapted to be engaged by a sliding clutch-member 9^e splined on shaft 8^g and having a groove engaged by a roller 9^d on a hand lever 9^a, which is pivoted at 9^b on bracket 9^c attached to bar 7. By properly shifting this lever 9^a, the clutch 9^c can be thrown into or out of engagement with the clutch 9^e, and consequently the gear 8^f can be caused to rotate with the shaft 8^g at will. Preferably after the plate is trimmed as above described and the tool 6^c retracted out of the way, the operator throws clutch 9^c into engagement with the gear 8^f, and the latter causes rack 8^c to move the tool carrier 8 forward on bar 7 until it

traverses the entire length of the plate in holder 3. The cutters 8^a on the tool carrier having been previously properly adjusted, operate to bore out or trim the interior of the plate P to the exact diameter desired; and as the plate is firmly expanded against the interior of the plate-holder the plate is truly and accurately bored so as to fit truly and snugly upon the plate-cylinder of the 10 press. When the carrier 8 has traversed through the plate the clutch 9^a is thrown out of engagement with the gear 8^c, and thereupon the weight 8^b draws the tool carrier back to the initial position out of the 15 way. Then the shaft 5 can be stopped and the finished plate removed.

An indicator or pointer 12 may be attached to one of the bearings 2 adjacent the cutting devices to indicate to the operator 20 the particular length of the finished plate and assist him in properly positioning the plate in the plate holder.

Having described my invention what I claim as new and desire to secure by Letters 25 Patent thereon is:

1. In combination, a rotary plate holder, means for rotating said holder, means for securing a tubular stereotype plate in said holder, a tool support fixedly supported in 30 the holder, a boring tool on said support, means for reciprocating said tool axially of the holder to true the interior of the plate, a cutting tool, and means for reciprocating the cutting tool transversely of the holder 35 to trim the end of the plate.

2. In combination, a cylinder adapted to contain a slotted tubular-plate, a longitudinal rib in said cylinder adapted to engage the slot in the plate, and adjustable devices 40 in the cylinder at one side of the rib adapted to engage one side of the slot in the plate and expand, and thereby secure the tubular-plate in said cylinder, means for rotating the cylinder, and means for boring the expanded plate.

3. The combination of a rotatable cylinder adapted to contain a slotted tubular plate, means for expanding the plate in the cylinder, a stationary bar extending axially 50 within said cylinder, a non-rotatable tool carrier slidably mounted on said bar, a rack connected with the carrier, a pinion engaging said rack, a driven shaft carrying said pinion, and a clutch for locking said pinion to the shaft, and means for rotating said cylinder to cause the tool to operate on the plate.

4. The combination of a rotatable cylinder adapted to contain a slotted tubular 60 plate, means for expanding the plate in the cylinder, a fixed bar extending axially of the plate in said cylinder, a tool carrier slidably mounted on said bar, a rack engaging said carrier, a pinion engaging said rack, a driven shaft carrying said pinion, a clutch

for locking said pinion to the shaft, means for throwing the clutch into and out of engagement, and means for retracting the rack bar when the clutch is disengaged; with means for rotating said cylinder to cause 70 the tool to operate on the plate.

5. The combination of a rotatable cylinder adapted to contain a slotted tubular plate, a bar extending longitudinally and attached to said cylinder and adapted to engage one edge of the slot in the plate, devices on the cylinder engaging the opposite edge of the slot to expand it in the cylinder, a tool support extending longitudinally of the cylinder, a tool carrier slidably mounted on 75 said support, means for reciprocating said carrier, and means for rotating the cylinder to cause the tool to operate on the plate.

6. A machine for finishing slotted tubular stereotype plates comprising a pair of bearings, a rotatable cylinder journaled therein, means for securing a tubular-plate in said cylinder, gearing for rotating said cylinder, a bar extending axially through said cylinder, a tool carrying slide on said bar, and 80 means for reciprocating said slide on said bar, substantially as described.

7. A machine for finishing stereotype plates comprising a rotatable cylinder adapted to contain a slotted tubular plate, 85 means for securing and expanding such plate in said holder, and gearing for rotating said cylinder, and means for boring the plate; with a transversely movable slide adjacent one end of said cylinder, and a 90 cutting and trimming tool carried thereby adapted to operate on the plate while the cylinder rotates.

8. The combination of a rotary cylinder adapted to contain a slotted tubular-plate 105 having a narrow longitudinal slot, and means engaging the slot in the plate for expanding and cramping such plate in said cylinder; with means for rotating said cylinder, and means for boring the expanded 110 plate.

9. In a machine for finishing tubular stereotype plates, a tubular holder, means for expanding a slotted tubular-plate placed within said holder so as to clamp the plate 115 therein, and means for rotating the holder.

10. In a machine for finishing tubular stereotype plates, a rotary cylindric holder, means for securing a slotted cylindric tubular-plate therein by expanding said plate in 120 the holder, a non-rotatable tool for operating on the tubular-plate within the holder, and means for moving said tool longitudinally of the holder during the rotation of the tubular-plate by the holder.

11. In combination, a rotary cylindric plate holder, adapted to contain a cylindric tubular-plate having a longitudinal slot, means for expanding such slotted tubular-plate within the holder, and means for ro- 130

tating said holder and plate; with a non-rotatable tool adapted to bore the interior of the plate, and means for reciprocating said tool through the plate as the latter is 3 rotated in the holder.

12. In combination, a rotary cylindric holder adapted to contain a cylindric tubular-plate, means for rotating said holder, means for expanding a slotted tubular 10 stereotype plate in said holder so as to hold its type face in close contact with the inner wall of the holder; a plate boring tool, and means for reciprocating said tool axially of the holder.

15. 13. In combination, a rotary cylinder adapted to contain a tubular plate having a narrow longitudinal slot, and means engaging the slot in the plate for expanding such 20 plate and cramping it in said cylinder; with a cutting tool adjacent the edge of the cylinder adapted to trim the edge of the plate while held in the cylinder.

14. The combination of a rotary cylinder adapted to contain a slotted tubular-plate 25 having a narrow longitudinal slot, and means engaging the slot in the plate for expanding and cramping such plate in said cylinder; with means for rotating said cylinder, and means for boring the expanded 30 plate; with a cutting tool adjacent the edge of the cylinder adapted to trim the edge of the plate while held in the cylinder.

15. In a machine for finishing tubular stereotype plates, a rotary cylindric holder, 35 means for securing a slotted cylindric tubular-plate therein by expanding said plate in the holder, a non-rotatable tool for operating on the tubular-plate within the holder, and means for moving said tool longitudinally of the holder during the rotation of the tubular-plate by the holder; with a cutting tool adjacent the edge of the cylinder adapted to trim the edge of the plate while held in the cylinder.

45. 16. In combination, a rotary cylinder adapted to contain a tubular-plate having a longitudinal slot, bell-crank levers pivoted on said cylinder, one arm of each lever projecting into the cylinder through openings 50 in the side thereof and adapted to engage one edge of the slot in the plate to expand the same in the cylinder, and means engaging the outer arms of the levers for adjusting them.

55. 17. In combination, a rotary cylinder adapted to contain a tubular plate having a narrow longitudinal slot, and means adapted to engage the slot in the plate from the exterior side thereof for expanding such plate 60 circumferentially and thereby cramping it in said cylinder.

65. 18. In combination, a cylindric plate holder adapted to contain a cylindric tubular-plate, means for rotating said holder; a boring tool, a stationary support therefor

extending into said holder; means for reciprocating said tool on said support through the holder to true the interior of the plate, a cutting tool, and means for reciprocating the cutting tool transversely of the holder 70 to trim the end of the plate while secured in the holder.

19. In machines for finishing tubular printing plates, a cylindric plate holder adapted to contain a tubular plate, means 75 for securing such a plate within said holder, and means for rotating the holder and plate; with a shaver, and means for traversing the shaver through the plate and plate holder.

20. In a machine for finishing tubular stereotype plates, a cylindric plate-holder 80 adapted to contain a single-page tubular-plate, means for expanding and securing said plate within said holder to rotate therewith; means for rotating the holder and 85 plate; a movable shaver adapted to traverse the plate-holder and plate to shave the latter; and means for reciprocating the shaver.

21. In a machine for finishing tubular stereotype plates, a cylindric plate-holder 90 adapted to contain a slotted tubular plate, an abutment in said holder adapted to engage one edge of a slot in the plate, means in said holder for engaging the opposite edge of the plate, and means for causing said devices 95 and abutment to separate so as to forcibly expand the plate in the holder.

22. In a machine for finishing tubular stereotype plates, a cylindric plate holder adapted to contain a slotted tubular plate, 100 an abutment in said holder adapted to engage one edge of a slot in the plate, means in said holder for engaging the opposite edge of the plate, and means for causing said devices and abutment to separate so as to forcibly expand the plate in the holder; and a 105 shaver adapted to traverse the holder and plate.

23. In a machine for finishing tubular stereotype plates, a cylindric plate-holder 110 adapted to contain a slotted tubular plate, an abutment in said holder adapted to engage one edge of the slot in such plate, means in said holder for engaging the opposite edge of the plate, and means for causing said devices and abutment to separate 115 so as to forcibly expand the plate in the holder; with means for rotating the holder and plate and a shaver adapted to traverse the holder.

24. In a machine for finishing tubular stereotype plates, a cylindric tubular plate holder, means for securing a tubular page-plate therein, a tool holder mounted axially of said plate holder, a rack bar for reciprocating said tool holder, a pinion for driving the rack-bar, a countershaft on which said pinion is mounted, gearing for driving the countershaft, and a clutch for locking the rack-bar pinion to said countershaft. 125 130

25. In a machine for finishing tubular stereotype plates, a cylindric tubular plate holder, means for securing a tubular plate therein, a bar extending axially through the 5 plate holder, a shaver slidably mounted on said bar, a rack-bar for operating said shaver; mechanism for driving the shaver, a pinion for driving the rack-bar, a counter-shaft on which said pinion is mounted, gear-10 ing for driving the countershaft from the plate holder driving mechanism, and a clutch for locking the rack-bar pinion to said coun-15 tershaft.

26. The combination of a rotary cylinder 15 adapted to contain a slotted single-page tubular-plate, means for rotating said cylinder, and means engaging the slot in said plate for expanding and cramping the same in 20 said cylinder, and means for shaving the plate while expanded.

27. In a machine for finishing stereotype plates, a rotary plate holder adapted to contain a single-page tubular plate, means 25 for expanding such a plate within said holder to secure it therein, a non-rotatable shaver for operating on the interior of the plate while it is carried by the holder, and means for moving said shaver longitudinally 30 of the plate during the rotation of the plate by the holder.

28. The combination of a rotatable cylinder adapted to contain a slotted single-plate tubular plate, an abutment in said cylinder adapted to engage one edge of the slot in said plate, devices on the cylinder engaging 35 the opposite edge of the slot in the plate to expand it in the cylinder, a bar extending axially of the cylinder, a shaver slidably mounted on said bar, means for reciprocating said shaver, and means for rotating the 40 cylinder to cause the shaver to operate on the plate.

29. In combination, a cylinder adapted to contain a slotted single-page tubular-plate, a longitudinal abutment in said cylinder 45 adapted to engage one edge of the slot in the plate, and adjustable devices in the cylinder at one side of the abutment adapted to engage the other edge of the slot in the plate and expand the tubular-plate tightly in said 50 cylinder; with means for rotating the cylinder and means for shaving the expanded plate.

In testimony that I claim the foregoing as my own, I affix my signature in presence of 55 two witnesses.

HENRY F. BECHMAN.
